CHARLES F. STODDARD, OF BOSTON, MASSACHUSETTS.

PRIME CONTROLLER FOR AUTOMATIC OR PARTLY-AUTOMATIC MUSICAL INSTRUMENTS.

1,294,844.

Specification of Letters Patent.

Patented Feb. 18, 1919.

Application filed November 4, 1911, Serial No. 658,477. Renewed July 11, 1918. Serial No. 244,490.

To all whom it may concern:

Be it known that I, CHARLES F. STODDARD, a citizen of the United States, and a resident of Boston, county of Suffolk, and State 5 of Massachusetts, have invented an Improvement in Prime Controllers for Automatic or Partly-Automatic Musical Instruments, of which the following description, in connection with the accompanying drawings, is a specification, like characters on the drawings representing like parts.

This invention relates to musical instruments which are operated wholly or partly automatically through a prime controller, 15 such, for instance, as a perforated note sheet.

An important object of the invention is to provide a means and a method for producing upon such an instrument the so-called "singing tone" effect which is a highly 20 refined and peculiarly beautiful effect characterizing some of the performances of the most eminent artists. Many attempts have been made in the art to produce wholly or partly automatically, or to enable an 25 operator to produce by following appropriate instructions in controlling a partly automatic instrument, the beauties and refinements which have distinguished the manual playing of artists from the productions of mechanical appliances. For 30 instance, it has been attempted to imitate automatically, or to enable an operator to imitate, the varying gradations in the loudness and softness of playing which are produced manually, and to imitate the 35 variations in tempo which contribute so largely to the beauty of manual rendition. Also, legato effects have been imitated with some success by appropriately 40 relating successive perforations of a note sheet, the notes of which are intended to be played legato. The present invention contributes to the art a refinement which is radically different from any which hitherto 45 has been attempted to be attained; and while this invention may be utilized advantageously in conjunction with other refinements, such as those above referred to, the invention, in and of itself, provides for the 50 production by automatic or partly automatic means, of one of the highest and most elusive refinements of rendition which only comparatively few of even the greatest artists are able to achieve manually.

Generally speaking, the so-called "singing tone" effect is produced by prolonging

or continuing accompaniment harmonies through a plurality of successive theme harmonies in such a manner as to provide a substantially sustained accompaniment background, so to speak, of a peculiar singing quality and perhaps of augmented volume. The combined effects of this character of accompaniment and the contrasting theme contribute a very beautiful quality to the 65 rendition. In providing for the production of this singing tone upon wholly or partly automatic instruments, the present invention opens a wide and altogether unique field of improvement in mechanical playing. 70

The invention will be described, for purposes of illustration, by reference to the art of player pianos such as are controlled by means of perforated note sheets. While it is not intended to limit the application of 75 the invention to that specific art, the illustration will suffice to exemplify and to indicate to those skilled in the art the general character and utility of the invention.

The usual player piano comprises a loud 80 or damper pedal mechanism by which the dampers of all or nearly all the strings are simultaneously removed from or applied to the strings. By such a mechanism the dampers may be held off the strings so that any 85 then sounding note will be sustained as will also the sympathetic vibrations of other strings. There are known variations of the mode of operation just described but they are immaterial to the present discussion and the 90 well known type of damper pedal mechanism suffices to exemplify what will be referred to, generically, hereinafter as "auxiliary note sustaining means"—"auxiliary" in the sense that the damper pedal mechanism or the like performs in general a sustaining function similar to that performed for each note by that part of its individual action which holds the string undamped so long as the actuating key is held depressed 95 100 or an equivalent operation is performed elsewhere in the action.

Such a damper pedal mechanism may be controlled, as already known in the art, by means of a perforated note sheet traversing 105 a tracker having appropriate vents. There are various known arrangements of perforations by which the note sheet may cause the dampers to be withdrawn from or returned to the strings.

The accompanying drawing shows at the left hand margin of the illustrative sheet,

one practicable form of sustaining perforations to operate, for example, a loud or damper pedal mechanism. As illustrated, these "sustaining perforations" consist each 5 of a series of substantially circular perforations separated by narrow bridges, each such series having the function and effect of one long continuous perforation, the bridges serving merely to strengthen the paper and 10 to avoid the difficulties encountered when long perforations are used, as well understood in the art. Any of the known equivalent arrangements of perforations for applying and withdrawing the dampers may be 15 employed within the scope of this invention. If a note sheet such as that diagrammed were used upon a player piano, for instance, having no tracker vent for controlling the loud or damper pedal mechanism, leaving 20 the latter to be controlled manually, or by a pedal, the sustaining perforations 6, 12, and 21 of the drawings would then serve as indications to the operator instructing him to withdraw the dampers from the strings when 25 the advance end of a series of the circular perforations reaches the tracker, and to return the dampers to the strings when the rear end of a series reaches the tracker. Thus, it will be possible to practice the invention by only partly automatic means, having 30 pedal operating perforations or the like replaced by instructive indications of the proper manner of operating the dampers.

The manner in which the invention may 35 be practised by means of the illustrative note sheet of the drawing when used, for example, upon a player piano, will be next described.

The note sheet represented in the drawing 40 is assumed to be perforated for playing a certain composition; and the note perforations 1, 2, 3, 4, etc., indicated by the full lines, are those perforations which would be cut in the usual note sheet according to the 45 accustomed practice which prevailed prior to this invention. The prolongations or extensions of the full line perforations, indicated by the dotted lines, exemplify, as presently described more fully, changes in the 50 cutting of the ordinary note sheet which are made to suit the objects of this invention.

The perforations 1, 2, 3, and 4, are assumed to be for accompaniment notes which are in harmony with the theme note of perforation 5, a note of long duration as represented by the length of its perforation. To contribute to the singing tone effect, it is desired that the accompaniment background be sustained for substantially the duration 55 of the theme note 5; and this is effected, in the illustrative example, by the sustaining perforation 6 which (when the note sheet is used on a player piano, for instance) holds the strings undamped throughout the length 60 of the perforation 6. Thus, the harmony of

the accompaniment notes 1, 2, 3, and 4, is sustained, regardless of the normal or usual length of the perforations 1, 2, 3 and 4.

The note of perforation 3 is repeated by the perforation 3^a which, in a player piano 70 for instance, merely repeats the percussion of the appropriate string to suit the particular composition being played; and that repeated percussion takes place while the original note sounded by the perforation 3 75 is still being sustained by the perforation 6. After the perforation 3^a has terminated, its note is prolonged throughout the remaining length of the perforation 6. In this manner, the tone initially sounded by the perforation 80 3 is continued throughout the length of the perforation 6, to contribute continuously to the accompaniment background for the theme note 5, the renewed sounding of the note by the perforation 3^a occurring at the 85 proper time to suit the composition to be played.

Similarly, the note of the perforation 2 is sounded again by the perforation 2^a; and the note of perforation 1 is sounded again by 90 the perforation 1^a. The entire accompaniment harmony for the first group of notes, as initiated by the perforations 1, 2, 3 and 4, is thus continued throughout the length of the sustaining perforation 6 which extends 95 nearly to the length of the theme note 5.

Just before the theme note 5 terminates, however, a second theme note is sounded by the perforation 7; and the latter, it is assumed for illustration, would not be in harmony with the accompaniment note sounded by the perforations 3 and 3^a. It is desired, therefore, to terminate the accompaniment note of the perforation 3^a before the theme note 7 is sounded and for this purpose the 100 105 sustaining perforation 6 is terminated in such relation to the advance end of the theme note perforation 7 as to avoid a discord.

It is further assumed, for illustration, that the theme note 7 is in harmony with the 110 accompaniment notes sounded by the perforations 1, 1^a, 2, 2^a and 4; and to produce the desired singing tone effect all these notes may be continued, preferably without interruption, from the first group of notes into 115 the second where they augment very desirably the accompaniment for the theme note 7.

The necessity for terminating the sounding of the accompaniment note of the perforation 3^a would have the effect, with 120 the normal cutting of note perforations indicated in full lines, of terminating also the notes sounded by the perforations 2^a and 4; and in order to prolong the sounding of the notes 2^a and 4, their perforations are suitably extended, for instance as illustrated by the dotted lines 2^x and 4^x, so as to continue their notes into the second group to contribute to the accompaniment background of the theme note 7. The normal length of the 125 130

perforation 1^a suffices to sustain its note as desired. By now utilizing the sustaining perforation 12, the harmony of the notes sounded respectively by the perforations 1^a, 5 2^a—2^x, and 4^x may be further sustained for any desired duration. According to the normal cutting of the note sheet to suit the composition being played, the note of the perforation 4—4^x is resounded by the perforation 10 4^b; the note of the perforation 2^a—2^x is resounded twice by the perforations 2^b and 2^c in succession; but the renewed sounding of these notes occurs while the notes are being sustained and while they are 15 contributing to the continued singing accompaniment effect.

A new note is introduced into the accompaniment by a perforation 10, that note being sustained, even after the perforation 10 terminates, 20 by the sustaining perforation 12, and being repeated by the perforation 10^a. Also, a new accompaniment note is introduced by the perforation 11.

The next following theme note sounded by 25 the perforation 9 is assumed to be a note which would create a discord with all previously played accompaniment notes except those sounded by the perforations 10^a and 11; and it is therefore desired to terminate 30 all of the discordant accompaniment notes in suitable relation to the beginning of the note 9. Therefore, the sustaining perforation 12 is terminated at a proper point to avoid the discord while the perforation 10^a is extended, 35 as by the prolongation 10^x, in order to sustain its note after the other notes have ceased to sound. The normal length of the perforation 11 suffices to serve the same purpose of continuing its note. These two 40 notes, 10^a—10^x and 11, are further sustained, even after their respective perforations have terminated, by the sustaining perforation 21, so that the harmony of the two notes is continued during the sounding of the note 9 and 45 throughout the perforation 21. New accompaniment notes 13, 14 and 15 are played during the sounding of the theme note 9; and they are likewise sustained by the perforation 21. The note of perforation 10^a—10^x is 50 twice resounded by the perforations 10^b and 10^c; the note of perforation 14 is resounded by the perforation 14^a; and the note of perforation 13 is resounded by the perforation 13^a; all to suit the composition to be played. 55 As in the other cases already discussed, the resounding of these notes occurs while the notes are still being sustained. The effect of the described illustrative arrangement of perforations may be best appreciated by 60 comparing the volume and harmony of successive accompaniment groups arranged as described, with the effects which would be produced by the normal cutting of the note perforations as indicated by the full lines in 65 the drawing. For instance, in the usual

note sheet heretofore employed and without the sustaining perforation 6, the notes of perforations 1, 2, 3 and 4, would have only the short durations represented by the lengths of the perforations, whereas when 70 combined with the sustaining perforation 6 they are sustained continuously as desired. Furthermore, in the usual note sheet, the note of perforation 4 would form no part of the accompaniment for the 75 theme note 7 and its contribution to the accompaniment would be altogether lacking throughout substantially the first half of the duration of the note 7 and until the note was resounded by the perforation 4^b. With the 80 described arrangement, however, the note initiated by the perforation 4 is sustained continuously throughout the playing of the theme note 5 and of the theme note 7, until the sustaining perforation 12 terminates. 85 Similarly, the note of perforation 2^a is carried from the first accompaniment group over to the second group and there sustained. The same is true of the note of perforation 10^a, as sustained by the extension 90 10^x and the sustaining perforation 21.

The foregoing will suffice to indicate to those skilled in the art one of the ways in which this invention may be applied in practice, *i. e.* by appropriately designing and 95 constructing a note sheet or the like so as to produce the singing tone effect. Such a note sheet as the one described may be made by reference to either an ordinary musical score or the record of a performance by a 100 pianist; the characteristics of the illustrative note sheet above described being supplied wholly or partly by editing, as it were, or revising the note sheet in accordance with the singing tone effect desired to be secured. 105 In the ordinary preparation of a note sheet from a score or record, as this has been done heretofore, the lengths of the note perforations have been made accurately proportional 110 to the time values of the notes indicated by the score or record. For the purpose of securing legato effects this practice has been varied somewhat by adding a slight increment of length to the rear end of each perforation, but that being for a purpose 115 entirely foreign to that of the present invention, it is here immaterial. The added increment of length for the legato effect is too minute to be comparable to the abnormal extension or prolongation of perforations such 120 as hereinbefore described; and the two produce results which are altogether different in kind. In the practice of this invention in connection with the note sheet, the time values of the notes indicated by the score or 125 record are in some instances practically disregarded, as for instance, in the case of the perforation 4—4^x shown in the drawing, it being assumed that the perforation 4 itself would be accurately representative of the 130

time value of the note as indicated by the score or record. Thus, it may be said that the perforation 4-4^x is "abnormally extended," and this expression will be employed for brevity in the claims to designate note perforations or other controlling elements which have extended or prolonged operative effects beyond the durations indicated for the respective notes by the score or record.

Likewise, for brevity, the expression "abnormally sustained," and variations thereof, will be used to designate generically the sustaining of notes beyond the respective durations indicated therefor by the musical score or record by reference to which the note sheet is made. For instance, the note of perforation 1 is "abnormally sustained" by the sustaining perforation 6; and the note of perforation 4 is "abnormally sustained" by the prolongation 4^x.

It is to be understood that the invention is not limited in its application, to the specific apparatus described above for illustration. I believe myself to be the first to conceive the manner in which the very beautiful refinement of the singing tone effect can be reproduced upon a mechanical instrument, and the first to devise means to that end.

Claims:

1. A note sheet for automatic musical instruments comprising a succession of groups of note-sounding perforations including perforations for sounding theme notes and accompaniment notes respectively; supplemental sustaining perforations for sustaining through substantially the duration of a group accompaniment notes sounded in said group, a selected accompaniment-note perforation of said group being abnormally extended to prolong the note thereof into a second group; and supplemental sustaining perforations to sustain notes of said second group and to sustain also, as a part of the harmony of said second group, the note of said abnormally extended perforation.

2. A note sheet for automatic musical instruments comprising a succession of groups of note-sounding perforations; including perforations for sounding theme notes and accompaniment notes respectively; means for abnormally sustaining the accompaniment harmony within a group; and means for abnormally extending from said group into the next following group those accompaniment notes which are in harmony with those of said next group, while terminating those accompaniment notes of the first group which would be discordant with the accompaniment harmony of said next group.

3. A note sheet for automatic musical instruments comprising a succession of groups of note-sounding perforations; means for abnormally sustaining notes within a group;

and means for abnormally extending from said group into the next following group notes which are in harmony with those of said next group, while terminating notes of the first group which would be discordant 70 with the harmony of said next group.

4. A note sheet for automatic musical instruments comprising a succession of groups of note-sounding perforations including perforations for sounding theme notes and accompaniment notes respectively; supplemental sustaining perforations for abnormally sustaining accompaniment notes of a group, a plurality of selected accompaniment-note perforations of said group being 80 abnormally extended to prolong the harmony thereof into a second group; and supplemental sustaining perforations to sustain notes of said second group together with the notes of said abnormally extended perforations.

5. A note sheet for automatic musical instruments comprising a succession of groups of note-sounding perforations; supplemental sustaining perforations for abnormally 90 sustaining notes of a group, a plurality of selected note-sounding perforations of said group being abnormally extended to prolong the harmony thereof into a second group and supplemental sustaining perforations to sustain notes of said second group together with the notes of said abnormally extended perforations.

6. A note sheet for automatic musical instruments comprising perforations for 100 sounding theme notes and accompaniment notes respectively, certain selected accompaniment note perforations being abnormally extended to contribute a singing tone effect; and perforations for controlling auxiliary note sustaining means abnormally to sustain other non-selected accompaniment notes.

7. A note sheet for automatic musical instruments comprising perforations for 110 sounding theme notes and accompaniment notes respectively, certain selected accompaniment note perforations being abnormally extended to contribute a singing tone effect; and longitudinally extending indications on the note sheet to denote the inauguration and maintenance of operation of auxiliary tone sustaining means to further contribute a singing tone effect.

8. A note sheet for automatic musical instruments comprising a succession of groups of note sounding perforations; longitudinally extending indications on the note sheet to denote the inauguration and maintenance of operation of auxiliary means for abnormally sustaining the notes of a group; a plurality of selected note sounding perforations of said group being abnormally extended to prolong the harmony thereof into a second group, and further longitudinally extending 12

indications on the note sheet to denote the inauguration and maintenance of operation of auxiliary note sustaining means to sustain notes of said second group together with the notes of said abnormally extended perforations.

9. A note sheet for automatic musical instruments comprising perforations for sounding theme notes and accompaniment notes respectively, certain selected accompaniment note perforations being abnormally extended to contribute a singing tone effect; and perforations for controlling auxiliary note sustaining means to cause said selected accompaniment notes to be sustained after their abnormally extended perforations have terminated.

10. A note sheet for automatic musical instruments comprising perforations for sounding theme notes and accompaniment notes respectively, certain selected accompaniment note perforations being abnormally extended to contribute a singing tone effect.

11. A note sheet for automatic musical instruments having note sounding mechanism, comprising perforations for controlling the sounding of notes by the note sounding mechanism and for abnormally sustaining selected notes to contribute a singing tone effect.

12. A note sheet for automatic musical instruments having note sounding mechanism,

comprising perforations for controlling the sounding of notes by the note sounding mechanism and for abnormally sustaining individual selected notes to contribute a singing tone effect.

13. In a note sheet for automatic musical instruments having note sounding mechanism, note perforations to sound their notes for their respective duration in the composition to be played; automatic means for abnormally sustaining a plurality of selected notes; and abnormally prolonged selected note perforations to sustain their notes after said automatic controlling means has ceased to operate.

14. A note sheet for automatic musical instruments comprising a succession of groups of note sounding perforations including perforations for sounding theme notes and accompaniment notes, respectively; a supplemental sustaining perforation for abnormally sustaining within a group a plurality of notes sounded in said group; and a selected note perforation of said group abnormally extended to prolong its note into a second group.

In testimony whereof, I have signed my name to this specification, in the presence of two subscribing witnesses.
